UNITED STATES PATENT OFFICE.

PIERRE ROTAT, OF LYON, FRANCE.

DEVICE FOR REGULATING THE ADJUSTMENT OF TOOLS ON MACHINE TOOLS.

Application filed January 18, 1921. Serial No. 438,127.

To all whom it may concern:

Be it known that I, PIERRE ROTAT, a citizen of the French Republic, of Lyon, France, have invented a certain new and useful Device for Regulating the Adjustment of Tools on Machine Tools, of which the following is a specification.

This invention relates to a device for regulating the adjustment of tools on machine tools.

To obtain exact regulation of tools on machine tools one is often obliged to wedge up these tools at certain points by means of one or more pieces or shavings of metal of any kind, and these pieces are selected of a thickness suitable to eventually obtain the total thickness desired. These regulations occur frequently in workshops and cause very appreciable loss of labour.

20 The present invention comprises a device which permits of obtaining instantly the height of wedging necessary as long as this height is within the limits found in the construction of the device.

25 The device consists of a cylindrical pin to which are connected several flat elements of different thicknesses, each comprising on one of their sides a lug constructed of thin sheet metal, and provided at its end with a circular hole through which a pin passes freely, which forms a connecting rod, and also forms an axis round which the flat elements are freely articulated.

30 The axial pin comprises a head at each end in order to retain the elements. The thickness of each of the elements constituting the block and the number of said elements are calculated according to the total thickness that may be required.

35 The annexed drawing shows by way of example a form of construction of the invention:

Fig. 1 is a view in section of a block comprising five elements superposed normally.

40 Fig. 2 is a plan view.

Fig. 3 is a view in section of the same block of which the two extreme elements are superposed, whilst the three others have been turned round the axle pin to take an opposite position.

45 Fig. 4 is a plan view of the device in the position of Fig. 2.

50 Fig. 5 is a further view in section of the same block showing the second and the fourth elements superposed, and the others in the opposed position.

Fig. 6 illustrates the application of the device to a tool-holder of a lathe.

The block illustrated comprises five flat elements *a*, *b*, *c*, *d*, *e* having similar surfaces and shapes but having different thicknesses. Each element comprises a lug formed of a very thin metal sheet, one of the ends of which is sunk flush in a recess in the corresponding block element and fixed by welding, riveting or other means, the shapes of the various lugs *g*, *h*, *i*, *j*, *k* being alike. The projecting ends of these lugs are provided with round holes, which are somewhat larger than the diameter of a pin *l* which connects them so that they can assume a certain obliquity to said pin when in the position shown in Fig. 3 with reference to the block elements *b*, *c*, *d*.

55 The block elements are retained on the pin *l* by the heads *l'*, *l''* of the latter, the head *l''* being formed after said members have been placed in position.

The pin *l* also carries a link plate *n* for the attachment of a chain *m* for supporting so the device when not in use.

60 The superposition of the block elements is made in their order of thickness, as shown in Fig. 1, and the thinnest element *e* at the top has its lug *k* at its upper surface so as to abut under the head *l'*, whilst the remaining elements have their lugs at their lower surfaces, the lowest lug *g* abutting against the head *l'*. This particular arrangement of the elements and the position of their claws is a feature of the invention, as it alone allows all the possible combinations of any of the five elements without those elements not in use being in the way.

65 By way of example, Fig. 3 shows the extreme elements *a* and *e* in use, which are brought into intimate contact and form a block for the tool *f* placed in the tool holder *p*. The three elements *b*, *c*, *d* not in use are turned around so as to be opposite to those in use, and however much their total thickness exceeds the space between the lugs *g* and *k* of the elements in use, they will assume a fan shaped position as shown in Fig. 3, owing to the thinness of the lugs and the sizes of the holes of the same embracing the pin *l*.

70 Fig. 5 shows the elements *b* and *d* in use and the position assumed by the remaining elements *a*, *c*, *e*.

75 Fig. 6 shows a tool *f* in the tool holder *p*, the block elements employed being *c*, *d*,

c; the elements not in use are not visible, the figure being a cross section.

It can be understood that to obtain various thicknesses of blocks in regular mathematical progression, the elements can be calculated and combined accordingly. For example, with five elements, if the element *a* is 4 millimetres thick, *b* 3 millimetres, *c* 2 millimetres, *d* 1 millimetre and *e* $\frac{1}{2}$ millimetre, the total thickness would be 10 millimetres and a half, and all intermediary thicknesses could be obtained by $\frac{1}{2}$ m. progressions.

The number of elements could be greater or less than five and the shape of same may vary as required.

What I claim as my invention and desire to secure by Letters Patent of the United States is:—

- 20 1. Device for regulating the adjustment of tools on machine tools, comprising a series of superposed flat elements, a flat lug provided with an orifice fixed on one side of each element, each lug being thinner than the wedge element to which it is fixed, a pin projecting through the orifices of said lugs with free play, and heads on each end of said pin to retain said lugs and said elements on said pin.
- 30 2. Device for regulating the adjustment of tools on machine tools, comprising a series of superposed flat elements of different thicknesses, a flat lug provided with an orifice fixed on one side of each element, the one surface

of a lug being flush with the one surface of an element, each lug being thinner than the respective wedge element to which it is fixed, a pin projecting through the orifices of said lugs with free play, and heads on each end of said pin to retain said lugs and 40 said elements on said pin.

3. Device for regulating the adjustment of the tools on machine tools, comprising a series of superposed flat metal elements of similar shape and having different thicknesses, the thinnest element being at the top of the series and the thicknesses of the remaining elements being increased for each successive element towards the bottom element, a flat lug formed of very thin plate 50 metal, and provided with a round orifice fixed on one side of each of said elements, the top surface of the lug attached to the top-most element of the series being flush with said top surface, and the under surfaces of the remaining lugs being flush with the bottom surfaces of their respective elements, a pin of round section extending through the orifices of said lugs, the diameter of the pin being substantially smaller than the 60 diameters of said orifices and heads on the ends of said pin.

In witness whereof I have signed this specification in the presence of two witnesses.

PIERRE ROTAT.
